UNITED STATES PATENT OFFICE.

ALANSON HENDLY SHERMAN, OF SOMERVILLE, MASSACHUSETTS.

FOG-ALARM.

SPECIFICATION forming part of Letters Patent No. 294,918, dated March 11, 1884.

Application filed December 26, 1883. (No model.)

To all whom it may concern:

Be it known that I, ALANSON HENDLY SHERMAN, of Somerville, in the county of Middlesex, of the Commonwealth of Massachusetts, have invented a new and useful Improvement 5 in Fog-Alarms, or machinery for sounding a horn for giving signals in a fog; and I do hereby declare the same to be described in the following specification, and represented in the 10 accompanying drawings, of which—

Figure 1 is a side elevation, and Fig. 2 a longitudinal and vertical section, of my improved fog-signalizer.

The nature of my invention is defined in the 15 claim hereinafter presented.

In the drawings, A denotes an upright steam boiler or generator provided at top with a self-closing cock, B, which opens from the boiler into a horn, C. The valve *a* of the said 20 cock is fixed to a spindle, *b*, which is provided with a spiral spring, *s*, for closing the valve upon its seat *c*. The said spindle slides in the body of the cock, and has a slot, *d*, to receive the shorter arm *e* of a bent lever, D, 25 the said lever being fulcrumed to an arm, E, extending from the cock. The longer arm *f* of the said lever terminates at its lower end in or has fixed to it a foot or rectangular plate, F, which answers not only as a stop for the 30 lever, but as a device for a cam, G, to bear against, in order to force the arm *f* upward. To the foot F and to the boiler a spiral spring, H, is attached and arranged as represented. The said cam G, formed as shown, has its 35 periphery an arc of a circle, the cam between the termini of the arc being recessed, as shown, to allow the foot F, on passing off the said periphery, to fall downward and bring up against the side of the boiler, it being so moved by the spring H. The arbor *g* of the cam has fixed on it a lantern-pinion, *h*, that engages with a gear, *i*, such arbor, pinion, and gear constituting part of a common 40 clock-work movement, I. This clock-work movement is to automatically revolve the arbor at a regular rate, in order for the horn to be sounded at proper intervals, and each of such soundings of it to be for a given period of time. From this it will be seen that the 45 fog-alarm is an automatic one. The spring H has a power greater than that of the valve-

closing spring *s*. Consequently, when the lever-arm *f* is free to move downward, it will be so moved by the spring H, and the valve of the cock will be opened and forced off its 55 seat, and will remain open until the lever-arm is raised by the cam and kept raised thereby. The moment the foot of the lever-arm passes off the end of the cam the spring H will draw downward the said arm until the 60 foot F brings up against the boiler. The valve of the cock will, by its spring *s*, be closed on its seat, while the lever-arm *f* is being raised and kept up by the cam.

From the above it will be seen that while 65 steam of sufficient force may be generated in and by the boiler, and the clock-work is in operation, the steam, at regular intervals and automatically, will be let into the horn to sound it.

I am aware that it is not new to have a fog-horn blown by air or steam by means or mechanism kept in operation by manual power, such being as shown in the United States Patent No. 28,837, and therefore do not claim 70 such. My apparatus, though involving various of the elements of the apparatus described in the said patent, has material differences, whereby it is caused to operate automatically to advantage—that is to say, it not only has 75 a cock provided with a spring to close its valve, but it has an additional and stronger spring to effect the opening of the valve; and, furthermore, it has a foot to answer, in manner as described, both as a stop to the valve-lever and as a device for the operative cam to work against. It also has a “clock-movement” for operating it automatically. It may be used on shipboard as well as on land.

I claim—

In combination with the steam-generator, the self-closing cock, and the horn arranged as described, the cock-valve-spindle-operating lever, its foot and actuating-spring, the rotary cam, and the clock-movement for revolving such cam, all being adapted substantially and to operate as set forth.

ALANSON HENDLY SHERMAN.
